UNITED STATES PATENT OFFICE.

MARSHALL C. ROGERS, OF WILLIAMS, CALIFORNIA.

BOX-COVER FASTENER AND REINFORCEMENT.

1,057,671.

Specification of Letters Patent.

Patented Apr. 1, 1913.

Application filed April 15, 1912. Serial No. 690,984.

To all whom it may concern:

Be it known that I, MARSHALL C. ROGERS, a citizen of the United States, residing at Williams, in the county of Colusa and State 5 of California, have invented new and useful Improvements in Box-Cover Fasteners and Reinforcements, of which the following is a specification.

My invention relates to a box cover fastening and reinforcing device.

It consists essentially of attachments at opposite ends of a cover, which attachments are adapted to interlock when the box is closed, and to which a seal may be affixed. 15 The interlocking attachments are extended so as to form reinforcements to strengthen the box ends and cover.

It also comprises details of construction which will be more fully explained by reference to the accompanying drawings, in which—

Figure 1 is a perspective view of the box, showing the cover partly removed. Fig. 2 is a perspective view partly broken 25 away, showing the other end of the box. Fig. 3 is a cross-section of the end of the box shown in Fig. 2. Fig. 4 is a cross-section of the other end of the box.

For the purpose of rapidly and securely 30 fastening covers upon boxes or crates of various descriptions, I have shown interlocking devices which may be readily closed and secured.

As shown in the drawings, A is a box and 35 B represents the cover. The sides of the box extend beyond the ends and have vertical cleats 2 secured to the box ends and flush with the projecting ends of the sides. Across the ends of the top are similar 40 cleats 3.

At one end of the box is secured a metal 45 plate 4, the ends of which extend beneath the cleats 2 and serve as a reinforce. The lower edge of the part 4 is secured to the end of the box as shown. The upper end is turned over into a hook-shape, as shown at 5; this portion projecting just above the upper edge of the box end. The cover portion B has a similar sheet of metal 6 which 50 extends beneath the cleat 3 and is secured therewith. The projecting edge is bent downwardly then with a reverse curve or hook portion 7; this hook portion 7 and the portion 5 of the fixed member being only 55 of a length equal to the distance between the vertical cleats 2. The engagement of these

two hook portions is made by lifting the opposite end of the box cover until these two can be hooked together, then the cover is let down and the hooks 5 and 7 engage and hold this end of the cover firmly in place. The opposite end of the box has a similar construction to that just described, and a metallic strip 8 is secured beneath the transverse cleat 3 on the top of this end of the box with the extensions beneath the cleat to reinforce this end of the cover. The part 8 has an outwardly turned hook portion 8^a, and these portions turn at right angles, as shown at 9, which serve as guides in closing the cover; these portions passing down between the vertical cleats 2^a at this end of the box, thus insuring the cover being properly placed.

Upon the end C of the box is fixed a 75 metal plate, which extends sufficiently below the top so that when its lower edge is fastened to the side of the box, the upper portion will have a certain amount of elasticity and movement to enable it to engage with the 80 member 8, which is secured to the end of the top of the box, as previously described. The ends of the lower part of this metal portion 10 extend above the vertical cleats 2^a and serve as braces. Therefore, as the upper 85 end is elastic and movable, when this end of the top is pressed down the two hook portions of the members 8 and 10 will interlock and engage and thus hold the cover in place. In order to secure this device, a tongue 11 90 is shown as secured to the upper edge of the end C and projecting through a slot in the spring plate 10. This tongue has a hole or opening through which a seal may be applied, thus insuring safety of the lock. 95 The box may be opened when the seal has been removed by springing the engaging members 8 and 10 until the interlocking tongues are separated, when the cover may be lifted about the opposite engaging interlocking ends until they are disengaged 100 and the cover can be removed. In this manner I am able to provide a secure cover and to reinforce the box end cover in such a manner that the edges will not be damaged 105 by ordinary rough usage.

Having thus described my invention, what I claim and desire to secure by Letters Patent is—

1. A box cover securing and reinforcing 110 device, said device consisting of plates extending horizontally across the ends of the

box having the upper long edges turned over into hook form and the lower edges secured to the box ends, the lower portion of the plates being extended at the ends beyond the corresponding ends of the hook portions, and vertical cleats upon the box ends beneath which said extensions are secured and plates on the cover of the box adapted to interlock with the hook portions of the first-
10 named plates.

2. A box cover securing attachment and reinforcement, comprising elastic hook plates

secured to the box ends and the cover ends respectively, having hook-shaped elastic engaging ends, and a strip thereto to extend 15 through one of said end plates and having a place for a seal attached thereto.

In testimony whereof I have hereunto set my hand in the presence of two subscribing witnesses.

MARSHALL C. ROGERS.
